(57) **CLAIM**

The ornamental design for a waste bag dispenser case, as shown and described.

DESCRIPTION

FIG. 1 is a top perspective exploded view of a waste bag dispenser case, shown in an open position for use with an environmental waste bag dispenser;

FIG. 2 is another top perspective view of the waste bag dispenser case thereof showing the top flap in a closed position, with an environmental waste bag dispenser installed inside the case;

FIG. 3 is a front view of the waste bag dispenser case thereof, shown in a closed front flap position with an environmental string;

FIG. 4 is a rear view thereof;

FIG. 5 is a right side view thereof, with the left side being a mirror image;

FIG. 6 is a top view thereof; and,

FIG. 7 is a bottom view thereof.

The waste bag dispenser and string are shown in broken lines to illustrate environment only and form no part of the claimed design.
